Chas. H. Luther

ATTORNEY:

UNITED STATES PATENT OFFICE.

ALBERT HENRY EDDY, OF EDGEWOOD STATION, RHODE ISLAND.

GAS-HEATER.

1,147,315.

Specification of Letters Patent.

Patented July 20, 1915.

Application filed April 14, 1915. Serial No. 21,298.

To all whom it may concern:

Be it known that I, ALBERT HENRY EDDY, a citizen of the United States, residing at Edgewood Station, in the county of Providence and State of Rhode Island, have invented a new and useful Improvement in Gas-Heaters, of which the following is a specification.

My invention has reference to an improvement in gas heating appliances and more particularly to an improvement in gas heaters of the Bunsen or high temperature type.

The object of my invention is to improve the construction of a gas heater of the Bunsen type, whereby a more perfect combustion and a hotter flame is produced, with a minimum amount of gas, than has heretofore been done.

Further objects of my invention are to simplify the construction and operation and to produce an intensely hot flame at a minimum of cost for gas.

My invention consists in the peculiar and novel construction of a gas heater of the Bunsen type, said gas heater having details of construction, as will be more fully set forth hereinafter and claimed.

Figure 1, is a side view in elevation of my improved gas heater. Fig. 2, is a top plan view of the heater, and Fig. 3, is a vertical sectional view of the heater taken on line 3. 3. of Fig. 2, and showing the lower fixed valve member in full lines.

In the drawing, 5 indicates the base member and 6 the burner member of my improved gas heater. The base 5 is a comparatively heavy rectangular shaped block of metal having a gas inlet pipe 7, connected to a horizontal gas inlet duct 8 controlled by a transverse tapered plug valve 9, having a port 10. This valve 9 has a coiled spring 11 intermediate the side of the base 5 and the head of a screw 12 in the end of the valve, which holds the valve tight under spring tension and a handle 13 on the opposite end for operating the valve, which is limited in its opening and closing movements by stop pins 14. 14 on the base 5, as shown in Fig. 1. The gas duct 8 connects with a central gas chamber 15, which first extends vertically through the base 5 and is internally screw-threaded at its upper and lower ends. A fixed valve member 16 is screwed into and closes the lower end of the gas chamber 15, and has the contracted cone-shaped upper end 17. A circular con-

centric boss 18 is formed on the top of the base 5, and a pilot-light tube 19 is secured to the base 5 and extends from the gas duct 8 upward to the top of the burner 6, as shown in Fig. 3.

The burner member 6 has a lower hollow circular dome-shaped portion 20 which fits over the boss 18 on the base 5, and merges upward into a straight contracted tubular portion 21, which is further contracted at its upper end in the form of a truncated cone-shaped burner tip 22. The dome shaped portion 20 has a series of air inlet openings 23. 23 in its sides, a raised bottom 24 in which is a series of holes 25. 25 and forms a mixing chamber 26. The bottom 24 carries a central vertical screw-threaded valve member 27 which screws into the upper end of the gas chamber 15 and has a central vertical gas duct 28 and a cone-shaped valve seat 29 on its lower end, in a position to engage with the cone-shaped end 17 of the fixed valve member 16, as shown in Fig. 3.

When in use the pipe 7 is connected to a source of gas supply, not shown, and the gas turned on. The gas at the end of the tube 19 is lighted and forms a minute pilot light. The valve 9 is opened, and the valve seat 29 raised out of engagement with the end 17 of the valve member 16, by turning the burner 6 until the required amount and force of gas through the burner 6 is obtained. The gas rushing through the duct 28, mixing chamber 26, portion 21 and tip 22 is ignited on the tip 22 by the pilot light on the tip of the tube 19. By this construction the amount of gas is regulated by the valve 9, the force of gas through the mixing chamber 26 is regulated by turning the burner 6 and the large size of the mixing chamber 26, as compared with the burner tip 22, gives a more perfect mixture of air and gas, a more perfect combustion and a hotter flame at the burner tip 22, than has heretofore been obtained. Any gas when in operation that may escape from the chamber 15 by the valve member 27 would rise through the holes 25. 25 in the bottom 24, and mix with the gas and air in the mixing chamber 26, thereby eliminating any odor of gas from the heater.

I do not wish to confine myself to the exact construction shown as the same could be changed within the scope of the appended claims.

Having thus described my invention I claim as new:—

1. A gas heater having a base, a central gas chamber in the base, a gas duct through the base into the gas chamber, a valve controlling the gas duct, a fixed valve member having a contracted cone-shaped end in the gas chamber, a burner having a comparatively large mixing chamber, air openings in the sides of the mixing chamber, a contracted tip and a central valve member having a gas duct and a cone-shaped valve seat coacting with the cone-shaped end of the valve member in the gas chamber, and means for rotatably and adjustably securing the burner to the base.
2. A gas heater having a base, a central gas chamber extending vertically in the base, a horizontal gas duct through the base into the gas chamber, a valve controlling the gas duct, a valve member in the gas chamber and closing the lower end of the gas chamber, a burner having a comparatively large mixing chamber, air openings in the sides of the mixing chamber, a contracted tip and a central valve member having a gas duct and coacting with the valve member in the gas chamber, and means for rotatably and adjustably securing the burner to the base consisting of screw-threading the valve member on the burner into the top of the gas chamber in the base.
3. A gas heater having a base, a central

gas chamber extending vertically in the base, a horizontal gas duct through the base into the gas chamber, a valve controlling the gas duct, a tube extending upward from the gas duct for a pilot light, a circular raised boss on the top of the base, a valve member in the gas chamber, a burner having a comparatively large circular mixing chamber over the boss on the base, air openings in the sides of the mixing chamber, a contracted tip, a raised bottom having a series of holes, and a central valve member having a vertical gas duct and coacting with the valve member in the gas chamber, and means for rotatably and adjustably securing the burner to the base, consisting of screw-threading the valve member on the burner into the top of the gas chamber in the base.

4. A gas heater having a base, a central gas chamber in the base, a gas duct through the base into the gas chamber, a fixed valve member in the gas chamber, a burner having a comparatively large inclosed mixing chamber, with air openings, a contracted burner tip and a valve member which enters the gas chamber in the base and coacts with the fixed valve member in the gas chamber, and means for rotatably and adjustably securing the valve member on the burner, in the gas chamber in the base.

In testimony whereof, I have signed my name to this specification.

ALBERT HENRY EDDY.
